PLUG SUPPORTING MEMBER FOR SPARK
PLUG CLEANERS

Hector Rabezzana, Flint, Mich., assignor to General Motors Corporation, Detroit, Mich., a corporation of Delaware

Application May 11, 1942, Serial No. 442,466

3 Claims. (Cl. 51—8)

My invention relates to spark plug cleaning devices of the type wherein a dry abrasive material is entrained by a stream of air under pressure and projected against the exposed inner end of a spark plug to be cleaned whereby oil, soot, encrusted carbon and like deleterious materials which accumulate upon the electrodes when the plug is in use, and which deposits are likely to interfere with the proper operation thereof, are removed from said inner end and from the electrodes between which the sparks pass, and the plug restored to substantially its initial condition and made available for further use, the same as a new plug. My invention is designed for use, particularly, with spark plug cleaning devices such as are disclosed in my application for patent for a Spark plug cleaner, filed September 4, 1941, Serial Number 409,475.

The object of my invention is to provide an improved device for supporting a spark plug while the electrodes thereof (which are exposed to burning gases when the plug is in use) are being cleaned by a jet of air and entrained abrasive material, as aforesaid; such supporting device being so designed and arranged as to prevent the abrasive material from injuring the external thread of the plug, which provides for the screwing thereof into an internally threaded hole in the wall of an internal combustion engine cylinder. That is the action of the jet of abrasive material is confined to the grounded shell electrode of the plug, and to the inner end of the central electrode thereof; and is excluded from the externally threaded shell of the plug so that said thread is protected from injury by the abrasive material.

The preferred form of my invention is illustrated in the drawing accompanying and forming a part of this application although it may be embodied in other forms, so long as such other forms come within the scope of the concluding claims wherein the features wherein my invention consists are particularly pointed out.

In the drawing:

Figure 1 is a view showing a section of my invention taken upon a vertical central plane; a spark plug being shown as supported thereby and various jet and cleaner features being shown, so that the device may be clearly understood.

Figure 2 is a view showing my improved plug supporting member in plan.

Figure 3 is a view showing my improved plug support as seen from a position below the same, looking up.

Figure 4 is a fragmentary view illustrating a 55 unglazed porcelain.

feature of my invention; this view being upon a larger scale than Figure 1 and a plug supported by the device being indicated by dotted lines.

Referring now to the drawing, the numeral 5 designates an angularly adjustable spark plug supporting member made, preferably, of vulcanized rubber, and having a passage extending axially therethrough and adapted to receive a plug to be cleaned, as illustrated in Figure 1; the lower end of said member having a depending annular portion 6 which extends into a sleeve 7 which is rotatable within a neck 8 fastened to the upper end wall 9 of a cleaner casing, all as in my application for patent hereinbefore referred to. 10 The supporting member has a series of peripheral notches 10 into which a spring-pressed detent 11 may enter to thereby hold said member 5 and the sleeve 7 with which it turns in definite angular positions while the plug is being cleaned, the same as in my application above noted.

The axially arranged spark plug receiving passage in the member 5 comprises a lower portion 12 of such diameter as to receive the externally threaded lower end A of the shell of a spark plug 25 (which screws into an internally threaded passage in a cylinder head or cylinder wall) and, preferably, with a larger upper portion 13 of such diameter as to receive the larger upper hexagonal portion B of said shell. Preferably the internal 30 diameter of this larger part of the plug receiving passage aforesaid is less than the maximum dimension of the hexagonal portion of the shell of the plug to be cleaned; so that when the plug is pushed into the passage in the member 5 provided for its reception, see Figures 1 and 4, the upper end of the neck 14 of the member 5 into which the upper end of the plug receiving passage extends, will yield as the plug is placed within the passage; and will squeeze the angles of the hexagon 35 40 as shown in Figure 1, and hold the plug in place within the passage provided for its reception while the plug is being cleaned.

Carried by the supporting member 5 so as to constitute a unitary part thereof, and so located 45 that the lower end of the threaded portion A of the plug to be cleaned may abut against it when the plug is in place within the passage aforesaid, is an annular member 15 made of a hard material which will be resistant to the abrasive action of the material used to clean the plug. Porcelain or like ceramic material, a suitable metal, or other material having the requisite hardness may be used for this member; although I recommend that it be made of a ceramic material, such as 50 unglazed porcelain.

The purpose of this member 15 is to prevent the abrasive material discharged by the nozzle C and used for cleaning the plug, from injuring the external thread upon the lower end A of the plug; this result being due to the fact that the abrasive material is prevented from impinging directly against the lower end of the thread by the inwardly extending ledge provided by said member, and by the fact that said member 15 provides a baffle which restrains the entrance of abrasive material into the space between the threaded part A of the plug and the passage 12 into which it extends.

Having thus described and explained my invention I claim and desire to secure by Letters Patent:

1. In a device of the class described, an angularly adjustable spark plug supporting member having an axial passage adapted to receive the threaded lower end of a spark plug to be cleaned; an annular member made of a material harder than said supporting member, located adjacent the lower end of said passage, and which annular member extends inward beyond the periphery of said passage so as to be engaged by the lower end of a spark plug within said passage; and means for discharging a stream of air and abrasive material against the lower end of a spark plug supported within said passage; and located above said annular member.

2. In a device of the class described, an angu-

larly adjustable spark plug supporting member having an axial passage adapted to receive the threaded lower end of a spark plug, and the upper end of which passage is enlarged so as to receive the enlarged upper end of a spark plug to be cleaned; an annular member made of a material harder than said supporting member located adjacent the lower end of said passage, and which annular member extends inward beyond the periphery of said passage so as to be engaged by the lower end of a spark plug within said passage; and means for discharging a stream of air and abrasive material against the lower end of a spark plug supported within said passage, and located above said annular member.

3. In a device of the class described, an angularly adjustable spark plug supporting member having an axial passage adapted to receive the threaded lower end of a spark plug to be cleaned; an annular member made of ceramic material disposed within and located above the lower end of said supporting member, and which annular member extends inward beyond the periphery of said passage so as to be engaged by the lower end of a spark plug within said passage; means for discharging a stream of air and abrasive material against the lower end of a spark plug supported within said passage, and located above said annular member.

HECTOR RABEZZANA.
